UNITED STATES PATENT OFFICE.

FREDERIC W. PRATT, OF VANCOUVER, BRITISH COLUMBIA, CANADA.

FILM-HOLDER.

1,234,800.

Specification of Letters Patent. Patented July 31, 1917.

Application filed September 21, 1915. Serial No. 51,904.

To all whom it may concern:

Be it known that I, FREDERIC W. PRATT, citizen of the Dominion of Canada, residing at Vancouver, in the Province of British Columbia and Dominion of Canada, have invented certain new and useful Improvements in Film-Holders, of which the following is a specification.

My invention relates to article holders and 10 more particularly to an improved album or folder constructed from a single sheet of material designed for holding films or negatives and prints developed therefrom.

An object of the invention is to provide 15 a novel means whereby the negatives or films may be held at the four corners and thus maintained perfectly flat and rigid and in such assembled relation as to be individually viewed with facility and ease.

20 A further object of the invention is to provide a means for holding the films, wherein, if desired, a particular film or negative may be readily removed and replaced, before and subsequent to printing, without 25 necessitating a lengthy search prior to such action.

The above and additional objects are accomplished by such means as are illustrated in their preferred embodiment in the accompanying drawings, described in the following specification and then more particularly pointed out in the claim which is appended hereto and forms a part of this application.

35 In describing my invention in detail reference will be had to the accompanying drawings wherein like characters denote like or corresponding parts throughout the several views, and in which:—

40 Fig. 1 is a perspective view of my improved album or folder, the cover flap being partly broken away; and

Fig. 2 is a fragmentary perspective view 45 illustrating the detail construction or formation of the film retaining tongues.

Before proceeding with a description of the drawings, I desire to call particular attention to the fact that while I have evolved my invention with reference to its use as 50 an album or folder for photographic negatives or films, the same, if desired, may be utilized as a means for holding developed negatives or prints.

Referring now to the drawings by numerals, 1 designates the cover flap, 2 the flap next adjacent the said cover flap, 3 the flap

of which the flap 2 is a part and 4, 5, 6 and 7 the duplicate negative or film holding flaps which, taken in connection with the flaps 1, 2 and 3 constitute the device of my invention as herein claimed.

60 Retaining tongues 8 are formed, one adjacent each of the respective four corners of the flaps 4, 5, 6 and 7 that a photographic film or negative 9 may be arranged therebeneath and thus held for view. Each of the mentioned tongues 8 is laterally offset that the film or negative may be arranged therebeneath with facility and ease. Retaining strips or tabs 11 are likewise formed at the 65 respective four corners of the mentioned flaps, one tab adjacent each of the mentioned tongues, the said tabs being adapted to hold, like the tongues 8, a film or negative for view.

70 Through the arrangement above noted it is evident that two films or negatives may be held by each flap, each of the mentioned films being placed face to face and against the flaps that either may be viewed without 75 detachment therefrom.

A pocket 12 is formed interiorly of the flap 2 that the developed films or prints may be retained or held. The inner surface of the flap 3 may be delineated with descriptive matter such as "hints to amateurs" or analogous useful information.

80 As stated, the retaining tongues are offset laterally with respect to the flaps 4, 5, 6 and 7 that the films or negatives may be viewed 85 and removed with ease. The sensitive surface of each film or negative is to be placed innermost that scratching (which invariably occurs) will not depreciate the film value. By holding the film in the manner stated, 90 a "curling" of the film is prevented. Access may be gained to a particular film without necessitating a lengthy search as heretofore. Each film may be individually viewed, removed and replaced, and the several films so inclosed and protected that light 95 cannot gain access thereto, the flaps 1, 2 and 3 completely embracing the flaps 4, 5, 6 and 7 in a minimum of space as shown to advantage in Fig. 1 of the drawings.

100 It will be understood that the above description and accompanying drawings comprehend only the general and preferred embodiment of my invention and that various minor changes in details of construction, proportion and arrangement of parts 105 may be made within the scope of the ap-

pended claim and without sacrificing any of the advantages of my invention.

Having thus fully described my invention, what I claim as new and desire to 5 secure by Letters Patent, is:—

A film holding device comprising a strip folded over and over into a plurality of film holding flaps, cover flaps of a size to inclose the film holding flaps when folded, 10 pairs of substantially diagonal slits being provided at the corners of the film-holding flaps, said slits being of arcuate formation with the convexed portion of each pair of

slits disposed adjacent each other, whereby the films may be placed at opposite sides of 15 a flap and their corners inserted through the slits thereby defining a connecting portion disposed across the corners of one film, and and a curved tab covering the corners of the other film at the opposite side of the flap. 20

In testimony whereof I affix my signature in presence of two witnesses.

FREDERIC W. PRATT.
